ACCORDION STRAP ATTACHMENT

Filed Dec. 12, 1928

INVENTOR,
VICTOR MENEGHETTI.
By *Martin Smith* ATTY.

UNITED STATES PATENT OFFICE

VICTOR MENEGHETTI, OF LOS ANGELES, CALIFORNIA

ACCORDION-STRAP ATTACHMENT

Application filed December 12, 1928. Serial No. 325,510.

My invention relates generally to accordions, and more particularly to a hand strap attaching means, and the principal object of my invention is to provide a relatively simple, practical and inexpensive attaching device that is applied to the end of the bass portion of an accordion and which serves as an adjustable attachment for the strap that engages and supports the hand of the player 10 that manipulates the bass keys of the accordion.

A further object of my invention is to provide an adjustable strap attachment for accordions that is very compact so as not to 15 interfere with the free manipulation of the instrument, and further to provide an attachment that may be easily and quickly manipulated to effect an adjustment of the hand retaining strap.

20 With the foregoing and other objects in view, my invention consists in certain novel features of construction and arrangement of parts that will hereinafter be more fully described and claimed and illustrated in the accompanying drawings, in which:

Fig. 1 is an end elevational view of the bass portion of an accordion and showing my improved strap attaching device applied thereto.

25 Fig. 2 is a horizontal section taken approximately on the line 2—2 of Fig. 1.

Referring by numerals to the accompanying drawings which illustrate a practical embodiment of my invention, 10 designates the 30 end wall or panel of the box or body that supports and contains the bass keys of an accordion, and which box or body includes a side wall 11 across the central portion of which passes a strap 12 that functions as a support 35 for the hand that operates the bass keys.

40 My device, which is designed to attach one or both ends of this strap to the ends of the bass portion of the accordion, comprises a substantially L-shaped bracket 13, one leg or flange of which is secured to the outer face 45 of the end panel 10 by screws or bolts 14, and formed through the central portion of the outwardly projecting flange or leg of this bracket is an aperture 15.

50 Secured in any suitable manner, preferably

by means of rivets 16, to the end of the hand supporting strap 12, is a plate 17, preferably formed of sheet metal having its central portion bent to form a transversely disposed tubular housing 18.

Passing through this housing and through the aperture 15 in bracket 13 is the threaded shank 19 of a screw or bolt, the head 20 of which depends against one end of the tubular housing 18.

55 Mounted on the threaded shank 19 on one side of the bracket 13 is an adjusting nut 21, and screw seated in said threaded shank on the opposite side of the bracket 13 is a lock nut 22.

60 By releasing the nuts 21 and 22 the screw 19 that is connected to plate 17 may be adjusted in either direction relative to the fixed bracket 13, thereby adjusting the tension of the strap 12 and after proper adjustment the 65 screw may be locked to the bracket by tightening the nuts 21 and 22 against said bracket.

65 In the playing of accordions, and particularly the larger types which are comparatively heavy, the hand retaining straps stretch 70 and become so loose that the hand is not supported in the proper manner to manipulate the bass keys, and my improved attachment is designed to function as an attachment for 75 one or both ends of the hand retaining strap 80 and to also provide simple and efficient means for adjusting the same.

75 The attachment is relatively simple in construction, is inexpensive of manufacture, and capable of being easily and quickly manipulated, and is very effective in performing the 85 functions for which it is intended.

80 It will be understood that minor changes 85 in the size, form and construction of the various parts of my improved accordion hand strap adjusting and attaching device may be 90 made and substituted for those herein shown and described without departing from the spirit of my invention, the scope of which is 95 set forth in the appended claims.

95 I claim as my invention:

1. An accordion strap attaching and adjusting device comprising a bracket adapted 100 to be positioned on the end of the accordion body, a plate secured to the end of the hand

retaining strap of the accordion with which the device is associated, a screw connected to said plate and passing through said bracket, and a nut mounted on said screw for engaging said bracket.

6 2. An accordion strap attaching and adjusting device comprising a bracket adapted to be positioned on the end of the accordion body; a plate secured to the end of the hand retaining strap of the accordion with which 10 the device is associated, a screw connected to said plate and passing through said bracket, and nuts mounted on said screw on opposite sides of said bracket.

15 3. In an accordion hand strap adjusting and attaching device, a bracket adapted to be secured to an accordion body, a plate secured to the hand strap of the accordion with which the device is associated, said plate being provided with a tubular housing, a screw loosely seated in said tubular housing and passing through a portion of said bracket, and an adjusting nut mounted on said screw and adapted to engage said bracket.

20 4. In an accordion hand strap adjusting and attaching device, a bracket adapted to be secured to an accordion body, a plate secured to the hand strap of the accordion with which the device is associated, said plate being provided with a tubular housing, a screw loosely seated in said tubular housing and passing through a portion of said bracket, and adjusting nuts located on said screw on opposite sides of said bracket.

25 5. In testimony whereof I affix my signature.
VICTOR MENEGHETTI.
